UNITED STATES PATENT OFFICE.

JOSEPH S. DUNCAN, OF CHICAGO, ILLINOIS, ASSIGNOR TO ADDRESSOGRAPH COMPANY,
OF CHICAGO, ILLINOIS, A CORPORATION OF ILLINOIS.

ADDRESSING-MACHINE.

1,231,576.

Specification of Letters Patent.

Patented July 3, 1917.

Application filed January 11, 1915. Serial No. 1,494.

To all whom it may concern:

Be it known that I, JOSEPH S. DUNCAN, a citizen of the United States, residing at Chicago, in the county of Cook and State of Illinois, have invented certain new and useful Improvements in Addressing-Machines, of which the following is a specification.

This invention relates in general to that class of printing machines now generally known as addressing machines but which are frequently used to print a great variety of information as well as addresses. More specifically the invention relates to a printing machine in which the force of the blow delivered by the platen is mechanically and automatically controlled.

It is desirable in the use of printing machines of this general class that the appearance of the impressions may be readily varied to suit the taste of the operator and that impressions from a plurality of individual printing devices present a uniform appearance. This is particularly true where the impressions are made contiguous to matter previously printed or typewritten since uniformity of the added matter with that already printed materially adds to the character of the work, and, therefore, to its value. To obtain these results it is necessary that the force of the platen blow be accurately gaged and made uniform throughout successive operations.

Printing devices bearing addresses and similar matter vary widely, however, in the amount of type surface presented, depending on the number of characters employed and the form of the type face. As is well known to persons familiar to the printing art, to obtain impressions of uniform appearance from forms carrying varying amounts of type surface it is necessary to vary the force of the platen blow in proportion to the amount of type surface presented by the printing device.

It is practically impossible to meet these ideal conditions, particularly in hand operable printing machines in which the force of the platen blow is controlled by the pressure applied by the operator since the operator can not accurately gage the degree of pressure applied.

It is an object, therefore, of my invention to provide in a printing machine means whereby the force of the platen blow may

be readily adjusted to make an impression of the desired appearance, the platen being mechanically and automatically controlled thereafter to deliver a blow of uniform force at each successive actuation of the operating means.

A further object of my invention is to provide means whereby the force of the platen blow may be rapidly varied by the operator to obtain uniform impressions from printing devices presenting varying amounts of type surface.

A still further object of my invention is to provide a machine to accomplish the desired purposes consisting of a minimum number of relatively simple and inexpensive parts, whereby the machine may be assembled at a cost which places it within the means of persons who, by reason of the work to be done require only a hand operable machine.

Other objects and advantages of my invention will be apparent as it is better understood by reference to the following specification in connection with the accompanying drawings in which—

Fig. 1 is a plan view of the machine;

Fig. 2 is a vertical section on the line 2—2 of Fig. 1;

Fig. 3 is a similar view of a portion of the machine showing the platen in printing position;

Fig. 4 is a vertical section on the line 4—4 of Fig. 3;

Fig. 5 is a rear elevation of a portion of the machine;

Fig. 6 is an enlarged detail of a portion of the controlling mechanism, and

Fig. 7 is a section on the line 7—7 of Fig. 6.

Referring to the drawings, 1 indicates the machine base which may be made in any suitable form to accommodate the mechanism and which is provided, in printing position, with an impression bed 2. Tracks 3 extend from the rear of the machine forwardly to a position beneath plate 4, secured to the base 1 and forming a support for the work. The upstanding flanged plates 5 are suitably secured to the base 1 adjacent the tracks 3 and form a magazine in which the printing devices are stored and from which they are fed by suitable devices, which form no part of my present invention and

are therefore not shown, forwardly on the tracks 3 to printing position above the bed 2 and thence to the magazine for used plates at the forward end and within the base 1 of the machine, where they rest upon a member 6 until removed from the magazine for reuse or storage. A ribbon 7 is disposed above the bed 2 and sufficiently spaced therefrom to allow the printing devices to pass between the ribbon and the bed. The ribbon 7 passes through openings 8 in the base 1 and is fed by suitable mechanism within the base, which mechanism may be of any of the well-known forms and is, therefore, not shown.

10 Pivottally mounted on pins 9, secured in the upstanding lugs 10 of the base 1 are the legs 11 and 11' of the impression member, the legs being joined at their extremities by a suitable connecting member 12 integral therewith. A platen 13 is secured to the connecting member 12 and is of suitable form to deliver the necessary blow to obtain an impression from the printing device. The leg 11 of the impression member 20 is provided with an extension 14 below its pivot extending into the base 1 of the machine.

15 Mounted on the pins 9 adjacent the legs 11 and 11' of the impression member are the legs 15 and 15' of the operating member, the legs being joined at their extremities by a connecting member 16 integral therewith and disposed beneath the leg 11 of the impression member. An extension 25 17 of the leg 15 of the operating member is provided with an operating handle 18, whereby the operating member may be moved about its pivot. The leg 15 of the operating member is provided with a rearward extension 19 and a tension spring 20 connects the pin 21 on the extension 19 with a pin 22 mounted in the base 1 of the machine and normally holds the operating arm in its uppermost position, as shown in Fig.

30 2, in which position the connecting member 16 engages the leg 11 of the impression member to hold it in its uppermost position. An extension 23 of the leg 15 below its pivot is provided with two arms 23' and 35 24' and a tension spring 24 connects the pin 25 on the arm 24' with a pin 26 on the extension 14 of the leg 11. Pivottally mounted at 27 in the base 1 is a latch 28 normally held in the position shown in Fig. 2 by a spring 29 mounted in a lug 30 of the base 1 and bearing against the end 28' of the latch 28. The opposite end of the latch 28 engages an abutment 14' on the extension 14 of the impression member 40 when the impression member is in uppermost position. A roller 31 is pivottally mounted on the arm 23' of the extension 23 and is adapted, when the operating member is turned about its pivot, to engage with an 45 abutment 32' on an extension 32 of the

latch 28 to turn the latch about its pivot against the spring 29 and release the abutment 14' on the extension 14 therefrom, whereby the impression member is allowed to be moved to printing position by the 50 spring 24.

From the foregoing it will be readily understood that by grasping the handle 18 and moving the operating member toward the position indicated in Fig. 3, the spring 24, 75 which connects the arm 23 and extension 14 of the operating and impression members, respectively, will be placed under tension, the spring tending to force the impression member downwardly to printing position, 80 the impression member being held, however, by the latch 28. When the operating member reaches the position indicated in Fig. 3, the roller 31 engages the abutment 32' on the extension 32 of the latch 28 and moves the 85 latch against the tension of its spring 29 to release the impression member which is then moved to printing position by the spring 24. When the handle 18 of the operating member is released the spring 20 returns it to its 90 normal position and the impression member is carried upwardly by the connecting member 16 until the latch 28 again engages the abutment 14', when the machine is ready for the second operation. It will be obvious 95 that the force of the blow delivered by the platen 13 is entirely independent of the force applied by the operator to the handle 18, the impression member being actuated by the spring 24.

To provide for regulation of the force of the blow delivered by the platen 13 I slidably mount a buffer bar 33 in the lug 34 and the rear wall of the base 1 so disposed as to be in the path of the abutment 14' on the extension 14 as the impression member moves to printing position, actuated by the spring 24. A spring 35 is disposed about the bar 33, between the rear wall of the base 1 and a pin 36, which passes through the 100 bar 33, and normally forces the bar 33 forwardly. The rear end of the bar 33 is cut away, as shown in Fig. 1, to form abutments 37 and 38 and a screw 39 is mounted in the rear abutment 38 to form an adjustable stop 105 against which a lever 40, pivottally mounted on a rod 41 secured to the base 1, normally rests. A lock nut 42 is provided to hold the screw 39 in position when adjusted. A lever 43 is pivottally mounted on the rod 41 adjacent the lever 40 and is joined therewith by a connecting member 44. A shaft 45, journaled to the front and rear walls of the base 1 and provided at its forward extremity with a handle 46, is operatively connected at its rearward extremity with the lever 43. A pin 47 is securely fastened in the side wall of the base 1 adjacent the forward end of the machine (Fig. 6) and a cam 48 is secured to the shaft 45 and adapted to 110 115 120 125 130

coöperate with the pin 47. The cam 48 is provided with a plurality of notches 49, in the present instance three, on its cam surface 50 which indicate three angular positions of the shaft 45. The cam surface 50 is so arranged with respect to the pin 47 that as the shaft 45 is rotated from left to right, the cam surface 50 will force the shaft 45 rearwardly and through levers 43 and 40 the bar 33 will be moved rearwardly 5 against the spring 35. When the handle 46 of the shaft 45 is turned in the opposite direction the spring 35 will cause the bar 33 to move forwardly.

15 As previously explained the end of the buffer bar 33 is disposed in the path of the abutment 14' on the extension 14 of the impression member and should be adjusted to be engaged by the abutment 14' before 20 the platen reaches printing position. A part of the force of the platen blow is, therefore, expended on the bar 33 which is resiliently held by the spring 35, the space between the abutment 37 and the end of the 25 adjusting screw 39 being sufficient to allow the bar 33 to be moved rearwardly against the spring 35. Since at any angular position of the shaft 45 it is rigidly held against forward movement by the pin 47 and con- 30sequently the levers 43 and 40 are similarly held, it will be readily understood that the position of the buffer bar 33 with respect to the abutment 14' may be easily adjusted by means of the screw 39. The relative posi- 35tions of the bar 33 and the abutment 14' control the force of the blow delivered by the platen, more or less of the force of the blow being expended on the buffer spring 35 before the impression is made. After the 40 machine has been initially adjusted to give an impression suited to a printing device representing a class presenting an average amount of type surface the force of the blow delivered by the platen will remain the same 45 at each successive actuation of the operating member regardless of the force applied by the operator and the appearance of the impression will be uniform so long as printing devices of this particular class are fed 50 to the machine. A secondary adjustment may be rapidly made by the operator to modify the force of the platen blow to suit printing devices presenting more or less type surface, depending on the class for 55 which the initial adjustment was made, by angularly adjusting the shaft 45, whereby the buffer bar 33 is moved toward or from the abutment 14'. In other words, if, with the shaft 45 in its foremost position with the 60 pin 47 at the lowest part of the cam 48, the buffer bar 33 is adjusted by means of the screw 39 to provide a platen blow sufficient to obtain a desirable impression from printing devices averaging a relatively 65 small amount of type surface, by angularly

turning the shaft 45, the shaft 45 will be moved rearwardly by the cam 48 and the corresponding rearward movement of the buffer bar 33 will result in lessening the retarding effect of the buffer bar on the platen 70 blow. A proper degree of force is thus provided for a class of printing devices presenting a relatively greater amount of type surface than those for which the initial adjustment was made. Further angular move- 75ment of the shaft 45 will result in a further adjustment of the buffer bar to provide for a class of printing devices presenting a still greater amount of type surface. While I have provided in the present machine for 80 three secondary adjustments for the reason that I have found this number to be sufficient in the practical operation of the machine it is obvious that a greater number of secondary adjustments may be provided. 85

It is believed that my invention will be readily understood from the foregoing without further description, and while I have shown and described as the preferred embodiment the application of my invention 90 to a hand operable printing machine it is obvious that it may be applied with equally advantageous results to power-operated machines and the appended claims are expressly drawn with a view to protecting my 95 invention in its application not only to hand operable machines of the type disclosed in the accompanying drawings but to all other printing machines to which it is applicable. 100

Furthermore, it will be manifest that various changes in the structural details disclosed may be resorted to without departing from the spirit of the invention or sacrificing any of the material advantages thereof. 105

I claim:

1. In a printing machine, the combination of an impression member, a platen carried thereby, means for applying a predetermined force to said impression member, whereby said platen is caused to deliver an impression blow, means for automatically controlling the force of the blow and means for returning said impression member to normal position after each actuation thereof. 110

2. In a printing machine, the combination of an impression member, a platen carried thereby, means for applying a predetermined force to said impression member, whereby said platen is caused to deliver an impression blow, resilient means for automatically controlling the force of the blow and means for returning said impression member to normal position after each actuation thereof. 120

3. In a printing machine, the combination of an impression member, a platen carried thereby, means for applying a predetermined force to said impression member, whereby said platen is caused to deliver an impression blow, adjustable means for au- 125

tomatically controlling the force of the blow and means for returning said impression member to normal position after each actuation thereof.

5. In a printing machine, the combination of an impression member, a platen carried thereby, means for applying a predetermined force to said impression member, whereby said platen is caused to deliver an impression blow, means for automatically controlling the force of the blow, means for adjusting said controlling means and means for returning said impression member to normal position after each actuation thereof.
10. In a printing machine, the combination of an impression member, a platen carried thereby, means for applying a predetermined force to said impression member, whereby said platen is caused to deliver an impression blow, means for automatically controlling the force of the blow, means for rapidly varying the effect of said controlling means, and means for returning said impression member to normal position after each actuation thereof.
15. In a printing machine, the combination of an impression member, a platen carried thereby, means for applying a predetermined force to said impression member, whereby said platen is caused to deliver an impression blow, means for automatically controlling the force of the blow, means for rapidly varying the effect of said controlling means, and means for returning said impression member to normal position after each actuation thereof.

6. In a printing machine, the combination of an impression member, a platen carried thereby, means for applying a predetermined force to said impression member, whereby said platen is caused to deliver an impression blow, means for automatically controlling the force of the blow, means for adjusting said controlling means, and means for rapidly varying the effect of said controlling means.

7. In a printing machine, the combination of an impression member, a platen carried thereby, manually operable means for applying a predetermined force to said impression member, whereby said platen is caused to deliver an impression blow, means for automatically controlling the force of the blow, primary means for adjusting said controlling means, and secondary means for rapidly varying the effect of said controlling means.

8. In a printing machine, the combination of an impression member having an extension beyond its pivot forming an abutment, means for applying a predetermined force to said impression member, whereby it is moved to printing position, resilient buffing means disposed in the path of travel of said abutment and adapted to be engaged thereby to control the force of the impression blow and resilient means to return said impression member to normal position after each actuation thereof.

9. In a printing machine, the combination of an impression member having an abutment thereon, means for applying a predetermined force to said impression member, whereby it is moved to printing position, and resilient buffing means disposed in the path of travel of said abut-

ment and adapted to be engaged thereby to control the force of the impression blow.

10. In a printing machine, the combination of a pivoted impression member having an extension beyond its pivot forming an abutment, means for applying a predetermined force to said impression member, whereby it is moved to printing position, and adjustable buffing means disposed in the path of travel of said abutment and adapted to be engaged thereby to control the force of the impression blow.

11. In a printing machine, the combination of an impression member having an abutment thereon, means for applying a predetermined force to said impression member, whereby it is moved to printing position, resilient buffing means disposed in the path of travel of said abutment and adapted to be engaged thereby to control the force of the impression blow, and means for adjusting said buffing means.

12. In a printing machine, the combination of a pivoted impression member provided with an extension below its pivot carrying an abutment, means for applying a predetermined force to said impression member, whereby it is moved to printing position, and buffing means disposed in the path of travel of said abutment and adapted to be engaged thereby to control the force of the impression blow.

13. In a printing machine, the combination of a pivoted impression member provided with an extension below its pivot carrying an abutment, means for applying a predetermined force to said impression member, whereby it is moved to printing position, and resilient buffing means disposed in the path of travel of said abutment and adapted to be engaged thereby to control the force of the impression blow.

14. In a printing machine, the combination of a pivoted impression member provided with an extension below its pivot carrying an abutment, means for applying a predetermined force to said impression member, whereby it is moved to printing position, and adjustable buffing means disposed in the path of travel of said abutment and adapted to be engaged thereby to control the force of the impression blow.

15. In a printing machine, the combination of a pivoted impression member provided with an extension below its pivot carrying an abutment, means for applying a predetermined force to said impression member, whereby it is moved to printing position, buffing means disposed in the path of travel of said abutment and adapted to be engaged thereby to control the force of the impression blow, and means for adjusting said buffing means.

16. In a printing machine, the combination of an impression member, a platen

- carried thereby, means for applying a pre-determined force to said impression member comprising an operating member and connecting means between said impression member and operating members whereby the force of the blow delivered by said platen is independent of the force applied to said operating member, and means for automatically controlling the force of the blow.
17. In a printing machine, the combination of an impression member, a platen carried thereby, means for applying a predetermined force to said impression member comprising an operating member and connecting means between said impression and operating members, whereby the force of the blow delivered by said platen is independent of the force applied to said operating member, and resilient means for automatically controlling the force of the blow.
18. In a printing machine, the combination of an impression member, a platen carried thereby, means for applying a predetermined force to said impression member comprising an operating member and connecting means between said impression and operating members, whereby the force of the blow delivered by said platen is independent of the force applied to said operating member, and adjustable means for automatically controlling the force of the blow.
19. In a printing machine, the combination of an impression member, a platen carried thereby, means for actuating said impression member comprising an operating member and connecting means between said impression and operating members, whereby the force of the blow delivered by said platen is independent of the force applied to said operating member, means for automatically controlling the force of the blow, and means for adjusting said controlling means.
20. In a printing machine, the combination of an impression member, a platen carried thereby, means for actuating said impression member comprising an operating member and connecting means between said impression and operating members, whereby the force of the blow delivered by said platen is independent of the force applied to said operating member, means for automatically controlling the force of the blow, and means for rapidly varying the effect of said controlling means.
21. In a printing machine, the combination of an impression member, a platen carried thereby, means for actuating said impression member comprising an operating member and connecting means between said impression and operating members, whereby the force of the blow delivered by the platen is independent of the force applied to said operating member, means for automatically controlling the force of the blow, means for adjusting said controlling means, and means for rapidly varying the effect of said controlling means.
22. In a printing machine, the combination of an impression member, a platen carried thereby, means for applying a predetermined force to said impression member, a resilient buffer adjustably mounted and adapted to be engaged by said impression member before said platen reaches printing position to absorb and thereby control the force of the blow delivered by said platen.
23. In a printing machine, the combination of an impression member, a platen carried thereby, means for applying a predetermined force to said impression member, a buffer bar resiliently mounted and adapted to be engaged by said impression member before said platen reaches printing position to absorb and thereby control the force of the blow delivered by said platen.
24. In a printing machine, the combination of an impression member, a platen carried thereby, means for applying a predetermined force to said impression member, a buffer bar resiliently mounted and adapted to be engaged by said impression member before said platen reaches printing position to absorb and thereby control the force of the blow delivered by said platen, and means for adjusting said buffer with respect to said impression member.
25. In a printing machine, the combination of an impression member, a platen carried thereby, means for applying a predetermined force to said impression member, a buffer bar slidably mounted and adapted to be engaged by said impression member before the platen reaches printing position, a spring operatively connected to said buffer bar and adapted to absorb and thereby control the force of the blow delivered by said platen, and means for adjusting said buffer with respect to said impression member.
26. In a printing machine, the combination of an impression member, a platen carried thereby, means for actuating said impression member, a buffer bar slidably mounted and adapted to be engaged by said impression member before the platen reaches printing position, a spring operatively connected to said buffer bar and adapted to absorb and thereby control the force of the blow delivered by said platen, a pivoted lever operatively connected to said buffer bar, and means connected to said lever for adjusting the position of said buffer bar with reference to said impression member against the action of said spring.
27. In a printing machine, the combination of an impression member, a platen carried thereby, means for actuating said impression member, a buffer bar slidably mounted and adapted to be engaged by said impression member before said platen reaches printing position, a spring operatively connected to said buffer bar and adapted to absorb and thereby control the force of the blow delivered by said platen, and means connected to said lever for adjusting the position of said buffer bar with reference to said impression member against the action of said spring.

reaches printing position, a spring operatively connected to said buffer bar and adapted to absorb and thereby control the force of the blow delivered by said platen, 5 a pivoted lever operatively connected to said buffer bar, means on said lever for adjusting the position of said buffer bar with reference to said impression member, and means connected to said lever to move said lever 10 about its pivot to rapidly vary the position of said buffer bar with reference to said impression member.

28. In a printing machine, the combination of a frame, an impression member 15 mounted thereon, a platen carried by said impression member, means for actuating said impression member, a buffer bar slidably mounted and adapted to be engaged by said impression member before the platen 20 reaches printing position, a spring operatively connected to said buffer bar and adapted to absorb and thereby control the force of the blow delivered by said platen, a pivoted lever operatively connected to said 25 buffer bar, a shaft connected to said lever, a cam on said shaft, and a pin secured to said frame and engaging said cam, whereby said shaft is moved longitudinally upon an angular movement thereof to move said lever 30 about its pivot and thereby adjust said buffer bar with respect to said impression member.

29. In a printing machine, the combination of a pivoted impression member, a pivoted operating member, each of said members being provided with extensions below 35 their pivots, a spring connecting said extensions, whereby said members are independently movable with respect to each other, a latch engaging with and normally restraining said impression member during a portion 40 of the movement of said operating member.

tion of the movement of said operating member, and means carried by said operating member for releasing said latch upon the continued movement of said operating member, whereby said impression member is actuated by said spring. 45

30. In a printing machine, the combination of a pivoted impression member, a pivoted operating member, each of said members being provided with extensions beyond their pivots, resilient connecting means between said extensions, whereby said members are independently movable relatively to each other, means for restraining said impression member during a part of the movement of said operating member, means for releasing said restraining means upon the further movement of said operating member, and means for returning said operating and impression members conjointly to normal position. 50

31. In a printing machine, the combination of a pivoted impression member, a pivoted hand operable operating member, each of said members being provided with extensions beyond their pivots, a spring connecting said extensions and adapted to actuate said impression member, a latch adapted to prevent actuation of said impression member during a portion of the movement of said operating member, means for releasing said latch upon the further movement of said operating member, and means for returning said operating and impression members conjointly to normal position. 55
